UNITED STATES PATENT OFFICE.

EDWARD SPENCER, OF ST. LOUIS, MISSOURI.

IMPROVEMENT IN HAND-STAMPS.

Specification forming part of Letters Patent No. **36,114**, dated August 5, 1862.

To all whom it may concern:

Be it known that I, EDWARD SPENCER, of the city and county of St. Louis, and State of Missouri, have invented certain new and useful Improvements in Hand-Stamps; and I do hereby declare the following to be a full, clear, and exact description of the same, reference being had to the annexed drawings, making part of this specification, in which—

Figure 1 is a side elevation of my said improved stamp, and Fig. 2 is a top view thereof with the upper part, A, removed.

I make my stamp in the form of a pair of squeezers hinged at the end, in the manner shown by the drawings. One part of said squeezers (which I shall call the "lower part") I make much thicker than the other and hollow it out, so as to fit it to receive a die, B, of any desired shape or configuration, and two rollers, D D, arranged one on each side of the said die. Upon said rollers I wind a ribbon, h, saturated with printers' ink, and stretch it over the face of the die, in the manner shown in Fig. 1. Under the bottom of the die I ar-

range a yielding bottom, so that the face of the die can adjust itself to the face of the platen A. In the frontend of the lower part I arrange a punch, E, to work in a corresponding die in the upper part or platen, A, by which means a hole can be punched in any article at the same time it is stamped, if that be desirable. The punch, however, may be omitted whenever it be necessary.

I arrange a spring, E, between the handles of the squeezers to press them open after the stamping has been accomplished.

This stamp may be used for a variety of purposes; but it is chiefly intended for the use of railway-conductors.

I claim as my invention—

The combination of the die B, the rollers C, and ribbon h with a pair of squeezers made substantially in the manner shown and described.

E. SPENCER.
